UNITED STATES PATENT OFFICE.

LAWRENCE GRIFFITH, OF YONKERS, NEW YORK.

SANITARY CATCH BASIN.

Application filed March 26, 1925. Serial No. 18,454.

This invention relates to improvements in catch basins designed to receive surface water drainage and to lead it into a sewer.

One of the main objects of the invention is to provide a means whereby a water seal will be formed between the sewer connection to the catch basin and the inlet through which the water flows from the catch basin to the sewer connection. The purpose of this is to at all times prevent a back-flow of sewer gas into the catch basin.

Another object of the invention is to provide means whereby the sewer connection may be located at a comparatively low level while the outflow from the catch basin may be arranged at a much higher level. The purpose of this is to increase the sediment capacity of the catch basin.

A further object of the invention is to provide a box-like casing, preferably of cast iron, adapted to be placed in the wall of the catch basin, the trap and water seal being within the casing so that said water seal will be maintained at all times to prevent a back-flow of sewer gas, regardless of the level of the water in the catch basin.

There are other important objects and advantages of the invention which will appear hereinafter.

In the drawing:

Fig. 1 is a vertical section through a catch basin showing my invention in applied position;

Fig. 2 a horizontal section through the basin showing the trap in plan;

Fig. 3 a vertical section through the trap on a larger scale taken on the line 3—3 of Fig. 1;

Fig. 4 is a vertical section taken on the line 4—4 of Fig. 3; and

Fig. 5 a perspective view of the trap.

Referring to the parts by numerals 1 designates a receiving basin of standard form located beneath a street gutter and sidewalk. The surface water drains into the basin through a grating 2 in the gutter and the basin may be entered by a workman and cleaned through a manhole 3. The basin is walled with any suitable material such as brick 4. The usual inclined drain pipe 5 leads from one side of the basin to the sewer and constitutes its outlet. In practice it has been found necessary to locate the pipe 5 at a depth of at least three feet below the street surface in order to protect it and

prevent its being broken by the shock and vibration caused by the street traffic.

My improved trap is in the form of a box-like casing 6 adapted to be built into the wall of the basin over the basin outlet or pipe 5. The lower portion of the casing 6 is formed to provide a trap well the depth of which is determined by an outlet opening 7 through the rear or outer side of the casing. The casing is formed with a flange 8 surrounding the opening 7, to which flange the pipe 5 is joined. The upper portion of the casing is centrally divided by a vertical partition 9 to thereby form an inlet chamber 10 and an outlet chamber 11 within the casing above the water in the well. The partition 9 extends downwardly to a substantial depth below the highest water level as determined by the lowest part of the outlet 7. The portion of the casing 6 enclosing the inlet chamber 10 extends considerably above the portion enclosing the outlet chamber 11 and is formed adjacent its upper end with an inlet opening 12 communicating with the inlet chamber. This opening 12 is formed in the front side or inner wall of the casing.

The inlet and outlet chambers are located side by side within the casing 6 and the casing is adapted to be mounted within the basin wall 4 with the plane of the two chambers disposed transversely to the direction of the basin outlet 5. The inlet opening 12 of the casing is therefore laterally offset from the outlet opening 7. This offset position of the inlet 12 provides clearance upon the front face of the casing for an observation and cleaning opening 13 formed in the inner wall of the casing in alignment with the outlet 7 at the rear thereof. This observation opening is normally closed by a slideable door 14 which is guided between guides 15 formed on the casing. The casing is formed with a seat 16 for the door, surrounding the opening 13, and both the seat and the guides 15 are inclined slightly from the vertical. The door 16 is adapted to be drawn upwardly to uncover the opening and its upward movement is limited by suitable stops 17 and 18 on the door and the guides, respectively. When the door is released it gravitates to closed position and its weight holds it against the inclined seat 16 to seal the opening 13. The stops prevent the door from being entirely removed and displaced.

The inlet 12 is located a material dis-

tance above the level of the outlet 7 and is covered exteriorly of the casing by a baffle hood 19 formed on the front of the casing. This hood extends across the opening and its lower end extends a suitable distance below the opening. As previously stated, the basin outlet pipe 5 is located approximately three feet below the street surface and it is the practice at present to cover the outlet 10 merely with a baffle hood similar to the hood 19. The outlet therefore remains unsealed until the water and sediment rise to the level of the baffle and sewer gas is free to escape into the basin. When the workman 15 removes the sediment from the basin he is required to remove the baffle hood and examine the outlet pipe 5 to make sure that it is not clogged. Frequently he fails to replace the baffle hood and as a consequence 20 the outlet remains permanently unsealed or else clogs with matter which the baffle is intended to exclude. It will be seen also that the capacity of the basin is limited to the level determined by the height of the 25 outlet 5, or of the baffle covering it. When the sediment rises to this level it is necessary to clean the basin to prevent the sediment from sealing the outlet and causing the basin to overflow. The large space 30 within the basin above the outlet is therefore wasted, as the sediment must not be allowed to rise above that point.

By locating the casing inlet 12 a considerable distance above the basin outlet, the 35 sediment capacity of the basin is greatly increased as will be seen in Fig. 1 of the drawing. When the water rises to the level of the opening 12 floating matter, such as sticks and the like, is prevented from passing 40 into the casing by the baffle 19 which prevents a direct lateral flow from the surface of the water to the inlet 12. It is necessary to clean the basin only when the sediment rises to the lower edge of the baffle 45 19. The capacity of the basin is thus greatly increased.

The trap well in the bottom of the casing remains permanently filled with water which 50 seals communication between the outlet and inlet below the partition 9 and prevents a back-flow of gas at all times, regardless of the water level in the basin. The pipe 5 and the trap are rendered readily accessible for inspection by the door 14. When the door 55 is raised the pipe may be viewed directly through the observation opening. This opening is preferably of material size in order to admit light and to permit cleaning of the trap well through it. The fall of 60 water into the trap well from the elevated inlet 12 agitates the water in the well and tends to prevent any dangerous accumulation of sediment therein. It will be understood 65 that the form of closure for the observation opening, as well as certain other details, may

be varied without departing from the spirit of the invention.

What I claim is:

1. A device of the class set forth comprising a casing forming a water trap well, an outlet for said well at one side of the casing and spaced above the bottom of the well to determine the water level therein, the casing having an observation and cleaning opening in its opposite side located in alignment with said outlet and at the same level, a movable closure for said opening, an inlet for said well above said water level and laterally offset from the outlet, and means separating the inlet from the outlet within the casing above the water level therein and for a depth below said level, whereby when the trap well contains water up to the water level it will form a water seal between said inlet and said outlet. 75 80 85

2. A device of the class set forth comprising a box-like casing adapted to be built into the wall of a catch basin and forming an enclosed water trap well at its lower portion, an outlet for said well through the outer wall of the casing and spaced above the bottom of the well to determine the water level therein, the casing having an observation and cleaning opening in its inner wall in alignment with said outlet and at the same level, a movable closure for said opening, an inlet for said well through the inner wall of the casing located a material distance above the level of the outlet and observation openings and laterally offset from the outlet and above the outlet a hood-like baffle means connected to the inner wall of the casing and extending across the inlet and below it to prevent a direct lateral flow of water from the catch 100 105 basin into said inlet, and means separating the inlet and outlet within the casing above the said water level therein and for a depth below the water level whereby water in said well will form a water seal between the inlet and the outlet. 110

3. A device of the class set forth comprising a casing forming a water well, an outlet for said well at one side of the casing, the casing having an observation opening in its opposite side located in alignment with the said outlet and at the same level, a movable closure for said opening, an inlet for said well above the outlet and observation opening, and a hood-like baffle means connected to the inner wall of the casing above the observation opening and extending across the inlet and below the lower margin of the inlet to prevent a direct lateral flow of water from the catch basin into said inlet and to form a water seal between the interior of the catch basin and the outlet opening. 115 120 125

In testimony whereof I hereunto affix my signature.

LAWRENCE GRIFFITH.
